(57) **CLAIM**

The ornamental design for a current transducer, as shown and described.

DESCRIPTION

1. Current transducer

1.1 : Perspective

1.2 : Perspective

1.3 : Front

1.4 : Back

1.5 : Top

1.6 : Bottom

1.7 : Left

1.8 : Right

The current transducer is shown with a symbolic break in its length. The appearance of any portion of the article between the break lines forms no part of the claimed design.
